STOP ROTATION MECHANISM ATTACHMENT

Thomas G. Bixby, Valparaiso, Ind., assignor to Phillips
Drill Company, Inc., Michigan City, Ind.

Filed Sept. 16, 1969, Ser. No. 19,157

Term of patent 14 years

Int. Cl. D8—02

U.S. Cl. D8—70

FIG. 1 is a side elevational view of a stop rotation mechanism attachment showing my new design;

FIG. 2 is a top end view of the stop rotation mechanism attachment shown in FIG. 1.

FIG. 3 is a bottom end view of the said stop rotation mechanism attachment shown in FIG. 1;

In use, the stop rotation mechanism attachment is associated with a rotary percussion hammer and acts as a clutch when installing self-drilling anchors.

I claim:

The ornamental design for a stop rotation mechanism attachment, substantially as shown.
